UNITED STATES PATENT OFFICE.

JAMES G. GRACEY, OF ST. LOUIS, MISSOURI, ASSIGNOR OF ONE-FOURTH TO EMANUEL LONGMEYER, OF ST. LOUIS, MISSOURI.

WIND-MOTOR.

1,352,952.

Specification of Letters Patent. Patented Sept. 14, 1920.

Application filed November 8, 1919. Serial No. 336,665.

To all whom it may concern:

Be it known that I, JAMES G. GRACEY, a citizen of the United States, and resident of St. Louis, State of Missouri, have invented 5 certain new and useful Improvements in Wind-Motors, of which the following is a specification.

This invention relates to improvements in a wind motor and has for its object a central 10 pivotally mounted staff on which is axially mounted a plurality of cross arms to which is attached balance vanes against which the winds contact for placing the motor in rotation.

15 A further object of my invention is to construct a motor having a plurality of balance vanes so arranged that when one of the vanes is placed in operation by the air-currents the opposite vane is automatically placed on approximately a horizontal plane thereby feathering the air so as to avoid counter action to the movement of the motor, these vanes being supported on shafts 20 axially mounted in a center pivotal stand- 25 ard.

The invention is especially adaptable for ornamental and advertising purposes. The vanes may be constructed of flags or banners or may consist of metallic sheets on which 30 may be painted or otherwise imprinted some advertisement.

The device is adaptable to be made of small construction so as to be placed on the 35 radiator cap of an automobile so that during the movement of the machine the motor is placed in operation and in such event the vanes may be of flags and the weights by which the vanes are balanced may be of some ornamental design such as an eagle or 40 the like and on the top of the pivotal support may be likewise some ornamented device or insignia which may be found most appropriate and adaptable.

Figure 1, is a side view of my invention.

45 Fig. 2, is a top plan view of the same.

Fig. 3, is a perspective view.

Fig. 4, is a detail enlarged view of a portion of the motor showing its general construction.

50 Fig. 5, is a detail perspective view of a portion of one of the vanes in modified form and the body of the vane portion being carried by a spring roller so that the same may

be rolled up when it is desired that the motor should not operate.

Fig. 6, is a detail cross sectional view of one of the vane frames showing its structure.

In the general construction of my invention and in referring to the drawings in detail 7 indicates a center post which is preferably of hollow construction. The same is connected to the base block 8 and projecting from the block is a pivot staff 9 which staff may be supported in any desirable 60 manner to the device on which the motor is carried and is so arranged as to permit the 65 mechanism to rotate.

On the top of the post 7 is placed a head 10 which may be of any ornamental design, 70 and in the top of the head may be supported a staff of an ornamented flag.

The center post 7 likewise acts as a bearing block for the support of rods 11 and 12 and said rods are held from side shifting by 75 means of a collar block 13 placed over the shaft and located on the inside of the post.

The rods 11 and 12 are connected to blocks 13' which act as a support for the vanes 14 and to the opposite side of the block is attached a short rod 15 provided with an ornamental end piece 16. Over the rods 11 and 12 and the short rods 15 are placed tubes 17 which likewise assist in preventing the 80 vanes from side shifting on the rods. To 85 the blocks 13' are attached the vanes which are in the form of a frame 18, the upper ends being connected to the blocks 13' and held thereto by a bolt 19, over which is a sleeve 20 and on the end of the bolt is placed 90 a head 21 which acts as a counter balance weight, and which is of a weight sufficient to properly counter balance the weight of the frame and the body portion 22 fastened within the frame; so that during the rotation of the motor when one of the vanes is placed approximately in vertical position by the air currents the opposite is automatically 95 turned to approximately a horizontal or feathering position thus relieving as much friction as possible and thereby permitting the motor to move quite rapidly.

The body portion 22 may be in the form of a fabric such as a flag as that shown in Fig. 1, or it may be of a plain piece of material on which may be imprinted some ad-

vertising matter, or it may be a strip or sheet of metal. This material is governed entirely upon the purpose on which the motor is to be used.

5 The vanes by means of their supporting bolts 19 will permit the same to be turned edgewise to the wind. The attaching vanes acting as a swivel, this action is necessary whenever it is desired to stop the motor or 10 place it out of operation in other words, the vanes may be turned by hand placing the same in the position at right angles to its operative position.

15 On the base portion 8 is attached a plurality of projecting arms 23 which are in a vertical as well as horizontal alinement with the motor rods and these arms act as a stop for the vertical movement of the vanes so that in the event of a severe gale the vanes 20 would not be placed in a circular movement on its own axis. However, these arms are not necessary because the ordinary tendency is that when the wind is operating against 25 one of the vanes the other holds it vertically on account of its feathering position and by means of the counter-balance weight the movement of the vanes operate in proper unison.

30 By referring to Fig. 5 of the drawing which is a modified form of a vane I show in this instance a spring roller mounted in the frame to which roller the body portion 22 is fastened and the spring rollers have bearing in the frame at the points indicated 35 by the numeral 24, and this structure is used for the purpose that when it is desired to prevent the motor from operating these vanes are rolled up on its frame so as to prevent a wind contact. In this instance I 40 construct the frame preferably out of wire bending it at the center into an eye 25 through which the bolt 19 is passed for clamping the vane tightly to the block 13.

45 This style of motor may be suspended instead of being mounted on the base, the suspended feature being adaptable for indoors so that the flags will act as the vanes are placed in movement by the draft. The de-

vice is very unique when used as an automobile ornament and the same may be planted 50 on lawns for decorative purposes.

The device is simple yet effective and operative in every particular and the same can be placed in rotation by a very mild breeze.

Having fully described my invention what 55 I claim is:

1. A wind motor comprising a central hollow rotatable stand, a plurality of arms supported by said stand, a vane supporting block carried by said arms, a vane frame 60 swivelly connected to said block, and a counter balance weight projecting above the block in alinement with the position of the vane frame, substantially as specified.

2. A wind motor of the character described comprising a center hollow stand, arms axially mounted in said stand, vane supporting blocks carried by said arms, a vane supporting frame swivelly attached to said blocks, a bolt supporting the vane 70 frame to said block, a counter balance weight attached to the end of said bolts and a body member supported in the vane frames to act as a sail with which the wind contacts, substantially as specified. 75

3. A wind motor comprising a plurality of axially mounted arms, a center support for said arms, vane supporting blocks rigidly attached to said arms, vane frames swivelly attached to said blocks, the position of the vanes on the blocks being so arranged that when one is vertical the opposite vane is horizontal, counter balance weights attached to the vane supporting blocks, said vane being adapted to be turned 85 edgewise to the wind for stopping the movement of the motor, substantially as specified.

In testimony whereof, I have signed my name to this specification, in presence of two 90 subscribing witnesses.

JAMES G. GRACEY.
